CLAIM

The ornamental design for a jeweler's metal mold assembly, as shown and described.

DESCRIPTION

FIG. 1 is a perspective view from the front of the jeweler's metal mold assembly of this invention with the mold sections open for completeness of disclosure; FIG. 2 is a perspective view from the back of the jeweler's metal mold assembly of FIG. 1 with the mold sections open for completeness of disclosure; FIG. 3 is a back elevational view of the jeweler's metal mold assembly of FIG. 1;

FIG. 4 is a side elevational view of the left side of the jeweler's metal mold assembly of FIG. 1 with the mold sections closed;

FIG. 5 is a top view of the jeweler's metal mold assembly of FIG. 1 with the mold sections closed; FIG. 6 is a bottom view of the jeweler's metal mold assembly of FIG. 1;

FIG. 7 is a front elevational view of the jeweler's metal mold assembly of FIG. 1; and

FIG. 8 is a side elevational view of the right side of the jeweler's metal mold assembly of FIG. 1 with the mold sections closed.
